UNITED STATES PATENT OFFICE.

JOHN W. MALLORY, OF NEAR IVANHOE, VIRGINIA.

BUCKLE.

1,233,092.

Specification of Letters Patent. Patented July 10, 1917.

Application filed July 26, 1916. Serial No. 111,466.

To all whom it may concern:

Be it known that I, JOHN W. MALLORY, a citizen of the United States, residing near Ivanhoe, in the county of Carroll and State 5 of Virginia, have invented certain new and useful Improvements in Buckles, of which the following is a specification.

This invention relates to certain new and useful improvements in buckles.

10 The primary object of the invention resides in the provision of a buckle which will be of simple construction and which will securely hold a strap engaged through the same without danger of tearing or otherwise 15 injuring the strap.

Another object of the invention resides 20 in the provision of a buckle of the above-stated character which will be formed of the minimum number of parts and constructed 25 in such manner that longitudinal strain upon a strap engaged through the same will cause a tightening of the buckle upon the strap.

25 A further object of the invention resides in the provision of a buckle of the above-stated character which will be composed of a pivoted member mounted in the body of the buckle and provided with opposite portions adapted to coöperate with the opposite 30 ends of the body to bind and clamp a strap engaged through said buckle without penetrating said strap.

35 With these general objects in view and others that will appear as the nature of the invention is better understood, the same consists in the novel combination and arrangement of parts hereinafter more fully described, illustrated in the accompanying drawings, and pointed out in the appended claim.

40 In the drawings forming a part of this application and in which like-designating characters refer to corresponding parts throughout the several views,

45 Figure 1 is a plan view of the complete buckle in use.

Fig. 2 is a longitudinal section through the same substantially on the plane of line 2—2 of Fig. 1.

Fig. 3 is a longitudinal section substantially on the plane of line 3—3 of Fig. 1.

Fig. 4 is a transverse section substantially on the plane of line 4—4 of Fig. 1, and

Fig. 5 is a detail perspective view of the pivoted member.

55 Referring more in detail to the drawings, 1 designates the body of the buckle which is

of substantially rectangular form and has the usual transverse bar 2, around which one end of a strap 3 is secured, the opposite end 4 of the strap being adapted to be passed 60 longitudinally through the body 1, and through the pivoted clamping member 5 as will be later clearly understood.

The pivoted clamping member 5 is formed of a single strand of wire having central 65 looped portions 6 formed along its longitudinal sides and offset downwardly for swinging movement upon the transverse bar 2, as clearly shown in Fig. 3 of the drawing. One end clamping bar 7 of the member 5 70 is extended in practically a horizontal plane and adapted for coöperation with one end 8 of the body 1 to clamp the end 4 of the strap passed between said clamping bar 7 of the member 5 and said end 8 of the body 1 as 75 shown in Figs. 2 and 3 of the drawing. It will be understood that the end 7 of the member 5 is positioned inwardly of the end 8. The opposite end 9 of the member 5 is extended in practically a vertical plane 80 above and inwardly of the end 10 of the body 1 for coöperation with the latter in forming an additional or secondary clamp for the end 4 of the strap 3, after the latter has been passed between said ends 9 and 10. 85 It will be understood that the end 4 of the strap 3 is first passed between the end 8 of the body 1 and clamping bar 7 and then between the ends 9 and 10 as shown in the drawings. 90

95 While the member 5 may be formed in any suitable manner, the wire from which said member 5 is produced preferably has one end bent to form one of the loops 6 after which the wires extend to form the clamp- 100 ing bar 7, then the opposite loop 6 and finally the end 9, the remaining extremity of the wire being extended downwardly to the position adjacent the first loop 6. This manner of forming the member will be apparent upon reference to Fig. 5 of the drawings. 105 It will also be seen by referring to the drawings that the loops 6 are offset from the clamping bar 7 and the end 9 of the member 5 and below the body 1, while said clamping bar 7 and end 9 are above the body 1. It will be further understood that the width of the bar 7 may be slightly greater than the width of the opening in the body 1, if desired, to prevent said bar 7 from 110 swinging through the body 1.

It will be evident that this form of buckle

will be highly efficient in use when employed in connection with harness straps and any longitudinal strain upon the strap will result in a binding action of the same against both ends of the body 1.

While the form of the invention herein shown and described is what is believed to be the preferred embodiment thereof, it is nevertheless to be understood that minor changes may be made therein without departing from the spirit and scope of the invention as claimed.

What I claim as new is:—

A buckle comprising a frame having a transverse bar extending across the same intermediate its ends, a clamping member formed from a length of wire, one extremity of the wire being bent to provide a bearing

and extending to provide a substantially U-shaped portion, the wire being then bent at the extremity of the U-shaped portion to provide a second bearing, the wire then being extended upwardly and bent horizontally to provide a clamping bar, which is out of the plane of the transverse bar of the U-shaped portion, the bearings being pivotally mounted upon the intermediate bar, the clamping bar of the clamping member and the adjacent end bar of the frame being adapted to bindingly engage a strap.

In testimony whereof I affix my signature in presence of two witnesses.

JOHN W. MALLORY.

Witnesses:

W.M. E. ROGERS,
LAURA E. ROGERS.
